UNITED STATES PATENT OFFICE

WILLIAM D. FURLOW AND LEWIS D. ROSE, OF INDIANAPOLIS, INDIANA

SPINDLE STRAIGHTENER

Application filed October 11, 1930. Serial No. 488,131.

This invention relates to a device for straightening bent automobile wheel spindles, and has for one of its objects to provide a novel device of this character which shall be simple and inexpensive and shall be adapted to permit spindles to be straightened easily and quickly.

With the foregoing and other objects in view, the invention consists in the construction, combination and arrangement of parts hereinafter fully described and claimed, and illustrated in the accompanying drawings, wherein:—

Figure 1 is a top plan view of the straightening device with a spindle arranged therein.

Figure 2 is a longitudinal sectional view taken on the plane indicated by the line 2—2 of Figure 1.

Figure 3 is a transverse sectional view taken on the plane indicated by the line 3—3 of Figure 2.

Figure 4 is a transverse sectional view taken on the plane indicated by the line 4—4 of Figure 2, and

Figure 5 is a transverse view taken on the plane indicated by the line 5—5 of Figure 2.

The spindle straightener comprises a body 1 which is of tubular formation and made from steel and which is adapted to receive the spindle to be straightened. The bore 2 of the body 1 is greater diametrically than the largest corresponding dimension of the spindle 3.

A fulcrum or bending pin 4 extends across the lower side of the bore 2 between the transverse center of the bore and the inner end thereof, the inner end of the bore being the one through which the spindle is inserted into the bore. The pin 4 has its end portions anchored in the sides of the body 1, and the intermediate portion of the pin is partly embedded in the lower side of the body. Guide pins 5 extend across the lateral sides of the bore 2 between the fulcrum or bending pin 4 and the inner end of the bore. Guide pins 6 extend across the lateral sides of the bore 2 between the transverse center of the bore and the outer end thereof. The guide pins 5 and 6 have their end portions anchored in the up-

per and lower sides of the body 1. The guide pins 5 are spaced apart for a distance greater than the guide pins 6. The spindle 3 rests upon the fulcrum or bending pin 4, the inner and larger end portion thereof is positioned between the guide pins 5, and the outer and smaller end portion thereof is positioned between the guide pins 6.

A cap screw 7 is threaded through the upper side of the body 1 centrally between the guide pins 5, and a cap screw 8 is threaded through said side of the body centrally between the guide pins 6. A follower or pad block 9 is positioned between the larger end portion of the spindle 3 and the lower end of the screw 7, and a follower or pad block 10 is positioned between the smaller end portion of the spindle and the lower end of the screw 8. The followers or pad blocks 9 and 10 are provided in their lower sides with arcuate recesses 11 for the reception of the end portions of the spindle 3, and are provided in their upper sides with concave recesses 12 for the reception of the rounded lower ends 7a and 8a of the screws 7 and 8.

In practice, the device is adapted for the reception of a spindle to be straightened by turning the screws 7 and 8 upwardly, and the spindle is inserted in the body 1 in a manner to arrange its inner and larger end portion between the guide pins 5 and its outer or smaller end portion between the guide pins 6. The spindle rests upon the fulcrum or bending pin 4 at a point between its end portions. After the spindle has been inserted in the body 1, the follower or pad blocks 9 and 10 are positioned upon the end portions of the spindle, and thereafter the screws 7 and 8 are turned downwardly into engagement with the follower or pad blocks. The spindle is locked in the body 1 by turning the screw 7 downwardly far enough to clamp the inner end of the spindle between itself and the inner end of the body. The spindle is straightened by turning the screw 8 downwardly, the resulting pressure on the spindle being applied thereto outwardly of the fulcrum or bending pin 4, with the result that the spindle is straightened. The bent spindle is

shown by broken lines and the straightened spindle by solid lines in Figure 2.

From the foregoing description, taken in connection with the accompanying drawings, it should be apparent that the spindle may be easily and quickly inserted and clamped in the device, that it may be easily and quickly straightened after being inserted in the device, and that it may be easily and quickly removed from the device after being straightened. To permit the removal of the spindle it is only necessary to turn the screws 7 and 8 upwardly.

While we have described the principle of the invention, together with the structure which we now consider the preferred embodiment thereof, it is to be understood that the structure shown is merely illustrative and that such changes may be made, when desired, as fall within the scope of the invention as claimed.

What is claimed is:—

1. A device for straightening a spindle, comprising a body provided with a bore for the reception of the spindle, a fulcrum extending across the bore and upon which the spindle rests, guides extending across the bore at right angles to the fulcrum, clamping means carried by the body and engaging the upper side of the spindle within the bore and at one side of the fulcrum, and bending means carried by the body and engaging the upper side of the spindle within the bore and at the opposite side of the fulcrum.

2. A device for straightening a spindle, comprising a body provided with a bore, a fulcrum or bending pin extending across the bore between the transverse center of the body and one end thereof, a screw threaded through the upper side of the body between said pin and end thereof, a screw threaded through the upper side of the body between said center and the other end thereof, guide pins extending across the bore at opposite sides of and parallel to said first screw, and guide pins extending across the bore at opposite sides and parallel to said second screw.

3. A device for straightening a spindle, comprising a body provided with a bore, a fulcrum or bending pin extending across the bore between the transverse center of the body and one end thereof, a screw threaded through the upper side of the body between said pin and end thereof, a screw threaded through the upper side of the body between said center and the other end thereof, guide pins extending across the bore at opposite sides of and parallel to said first screw, and guide pins extending across the bore at opposite sides and parallel to said second screw, all of said pins having their ends embedded in the body and said first guide pins being spaced apart for a distance greater than said second guide pins.

4. A device for straightening a spindle, comprising a body provided with a bore for

the reception of the spindle, a fulcrum extending across the bore and upon which the spindle rests, guides extending across the bore at right angles to the fulcrum, clamping means carried by the body and engaging the upper side of the spindle within the bore and at one side of the fulcrum, and bending means carried by the body and engaging the upper side of the spindle within the bore and at the opposite side of the fulcrum.

In testimony whereof we heretunto affix our signatures.

WILLIAM D. FURLOW.
LEWIS D. ROSE.
